Primary Examiner — Keli L Hill(74) *Attorney, Agent, or Firm* — Thorpe North & Western, LLP(57) **CLAIM**

The ornamental design for the mini wireless speaker, as shown and described.

DESCRIPTION

FIG. 1 is a rear perspective view of the mini wireless speaker in accordance with the invention;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof; and,

FIG. 7 is a rear elevation view thereof.

The broken lines shown are included for the purpose of illustrating portions of the mini wireless speaker that form no part of the claim.
